UNITED STATES PATENT OFFICE

FRANK A. LUNDQUIST, OF CHICAGO, ILLINOIS.

CALLING DEVICE FOR TELEPHONE-EXCHANGES.

No. 822,965.

Specification of Letters Patent.

Patented June 12, 1906.

Application filed July 11, 1904. Serial No. 215,981.

To all whom it may concern:

Be it known that I, FRANK A. LUNDQUIST, a citizen of the United States of America, and a resident of Chicago, county of Cook, and 5 State of Illinois, have invented certain new and useful Improvements in Calling Devices for Telephone-Exchanges, of which the following is a specification.

My invention relates to calling devices for 10 telephone-exchanges, and has for its object improvement in the construction and operation of such devices.

The device shown in the present application is particularly adapted for large automatic exchanges where the numbers given to 15 the stations include three, four, or more figures, and it has provisions by which the number called is automatically registered.

In the accompanying drawings, Figure 1 is 20 a front elevation showing the position when a station has been called. Fig. 2 is a similar elevation with the front plate and surrounding case removed. Fig. 3 is a section on line 3 3 of Fig. 1. Fig. 4 is a section on line 4 4 of Fig. 3. Fig. 5 is an enlarged detail of the operating mechanism. Fig. 6 is a detail of one of the registering-dials. Fig. 7 is an enlarged detail of the receiver-hook and parts operated thereby, and Fig. 8 is a detail of one of 25 the contact-springs shown in Fig. 4.

On the front cover of an ordinary box A is 30 a plate A', to which is attached a cylindrical casing A''. Secured to the cover of the box A and extending through the center of the casing A'' is a spindle B. Secured to the inner end of the spindle B is a segment of the 35 toothed wheel B' and a spring B'', which acts to retain the devices in the position shown.

On the front end of the spindle B is secured 40 a plate C, and on this plate is a lever C', movable between two pins C² and C³. (See Figs. 2 and 5.) Loosely mounted on the extreme end of the spindle B is a lever D, provided 45 with a pointer D', adapted to sweep over the numbered dial D² on the cover D³ when said lever is moved by hand. The lever D rests adjacent to the outer and upwardly-projecting end of the lever C', and when the lever D is moved by hand to the right it swings the 50 lever C' on its pivot from contact with pin C² to contact with pin C³. A further movement 55 of the lever D then moves the plate C and the spindle B. Such movement of the spindle B rotates the segment B' against the action of the spring B'' and causes its teeth to strike the inclined lips E' and F' on the insulated

springs E and F. Adjacent to these springs are other insulated springs E² and F². These parts are so arranged that upon moving the segment only one tooth strikes the lip E'; but the number of teeth that strike the lip F' is determined by the length of the movement. The lips E' and F' are so inclined that when the segment B' is moved forward in the direction of the arrow of Fig. 4 the springs E and 60 F are moved away from the contact-springs E² and F²; but upon a backward movement E makes electrical connection to E² and F makes electrical connection to F². The arrangement is also such that upon a backward movement following a forward movement either one or a series of contacts are made with F², and then one contact is made with E².

F² and E² represent different lines over 75 which electrical impulses are sent by a movement of the calling device, and the spacing of the teeth on the segment B' is so related to the numbers on the dial D² that the number of contacts made with F² corresponds to the 80 number to which the pointer D' had been previously moved by hand.

On the segment B' is a pawl B⁴, which engages a ratchet-wheel B⁵. This ratchet-wheel is connected to a gear B⁶, which meshes 85 with a pinion on a governor mechanism B⁷. When the segment B' moves forward as a result of a manual operation of the lever D, the pawl B⁴ rides over the teeth of the ratchet-wheel B⁵; but when these parts return to 90 their normal position as a result of the action of the spring B² the pawl drives the ratchet-wheel, and hence the governor mechanism. By this means the speed at which contacts are made with F² is regulated. 95

The spacing of the ratchet-wheel B⁵ corresponds to the spacing of the teeth on the segment B', and the ratchet-wheel and pawl are made so that for each tooth passed the pawl will make a distinct "click" that can be 100 heard by the operator who moves the handle D.

The first click corresponds to "0" on the dial D², the second click to the figure "1," and so on, or by shifting the "0" to the 105 other end of the figures on the dial the number of clicks can be made to correspond to the number to which the pointer D' is moved. By knowing the arrangement and counting the clicks a subscriber can operate his calling 110 device in the dark.

On one part of the plate C is a screw C'

Figs. 2 and 5, and arranged to slide on this screw and the spindle B is a slotted plate or slide C⁵, having ratchet-teeth on its opposite edges. A spring C⁶ normally holds said slide to the right.

On the lever C' is a pawl C⁷, provided with a tail engaging the screw-head C⁴. A spring C⁸ normally holds the lever C' and pawl C⁷ in the position shown in the drawings and with 10 said pawl disengaged from the adjacent ratchet-teeth on the slide C⁵. When the lever C' is moved on its pivot, as a result of manipulating the lever D, the pawl C⁷ engages the teeth on the slide C⁵ and moves said slide 15 one step to the left. This step is completed during the time the lever C' is moving from pin C² to pin C³, a further movement of the lever C' resulting in a movement of the plate C and all the parts carried thereby. When 20 the hand-lever D is released, the spring B² returns the plate C' to its normal position, and the spring C⁶ moves the pawl C⁷ to the right preparatory to again engaging and moving the slide C⁵. In the meantime the 25 holding-pawl C⁹ engages the teeth on the opposite side of the slide C⁵ and prevents it from returning to the right until said pawl has been released.

Loosely mounted on the spindle B are a 30 series of disks G, part of each of which is cut away, leaving on one side a rim G', having thereon a series of figures. On the solid part of each disk is a series of pins G², spaced to correspond to the spacing of the numbers on 35 the rim G'. As the result of part of the metal of a disk being cut away these disks are unbalanced and naturally tend to come to a rest with the heavy side down. Secured to any convenient stationary part, as the 40 plate A', is a pin G³, Fig. 6, so located as to stop the gravity movement of the disks at a certain point and maintain their numbers at a definite relationship to each other. These disks are of graduated sizes and arranged so 45 that when viewed in front the numbers on the rear disks are seen beyond the edges of the forward disks. The radial distance between a row of pins G² on one disk and a similar row on the next adjacent disk is equal to 50 the spacing of the ratchet-teeth on the slide C⁵. Also loosely mounted on the spindle B and separating the disks G from each other are a series of washers G⁴, provided with projections G⁵, that engage a pin G⁶. This pin 55 prevents the washers from turning on the spindle, while it permits them to slide to a limited extent.

A receiver-hook H is pivoted at H' to the plate A' and has a portion H², which lies behind and slightly removed from the rear one of the washers G⁴. Secured at a convenient place on the plate A' is a spring J, that projects between the part H² and the rear washer G⁴. These parts are so related to each other 65 that when the hook H is at its elevated posi-

tion the part H² forces the spring J against the rear washer G⁴, and when the hook is at its lower position the spring falls away from the washer. The result of this is that when the hook H is elevated the disks G are clamped 70 between the washers G⁴, so that when the disks are moved they are held in the moved position by friction with the washers. When the hook is depressed, this friction is released and any moved disks G are free to fall by 75 gravity back to their normal positions.

Secured to the slide C⁵ is a spring-pawl K, which when the slide is in its normal position projects back adjacent to and just outside of the row of pins G² on the largest disk 80 G. When the handle D is moved by hand, the preliminary movement from its normal position to a position about half way to "0" of the dial moves the lever C' against the pin C³, and consequently moves the slide one 85 step to the left, bringing the pawl K in line with the outer row of pins G² on the largest disk G. The rest of the movement of the hand-lever D to "0" turns the plate C on the spindle B far enough for the pawl K to ride 90 over and drop behind the first pin G² on the largest disk G. A further movement of the hand-lever D moves the pawl K over successive pins G², said pins being so spaced that 95 there is one pin for each figure on the dial D².

When the hand-lever D is released, the spring B² returns the spindle B and the parts secured thereto, to normal position. In thus returning, the pawl K engages the pin G² which it last passed over and moves the disk 100 G a corresponding distance. As the hook H is supposed to be in its elevated position when this last operation is performed, the moved disk is held in its moved position by the washers G⁴ in contact with its opposite 105 faces.

The preliminary part of the next forward movement of the hand-lever D in a similar manner advances the pawl K to the row of pins on the next disk, and a further movement of the lever moves the pawl over the pins in the same manner it would over a ratchet-wheel. When the lever is again released, the second disk is moved a distance corresponding to the movement made by 110 hand-lever D. In the same way the third and fourth disks are moved a distance corresponding to movements made by the hand-lever D.

In the cover D³ is an opening D⁴, through 115 which the rims G' of the disks G may be seen. The figures on the rims of the disks are so arranged that when the lever D has been moved with its pointer D' to any figure on the dial D² the result will be that the same figure will 120 appear at the opening D⁴ on the particular disk which happens to have been moved. Thus Fig. 1 shows at the opening D⁴ the number "3,468" and indicates that the hand-lever D was successively moved to the figures 130

"3," "4," "6," and "8" on the dial D². These movements of the disks G may be made either on the forward or the backward movements of the lever D. They are shown as being made by the same movement that makes the electrical contacts, and these are preferably made by the backward movements, because those movements are spring-operated and governed for speed, while forward movements by hand are very variable.

Pivoted on the plate A' is a bracket M, which is normally held against a pin M' by a spring M². In said bracket is a rod M³, provided with a beveled collar M⁴ and normally held to the left by a spring M⁵. On the hook H is a projection H³, adapted to engage the collar M⁴ when the hook is moved. When the hook is moving upward, the projection H³ causes the bracket M to turn on its pivot, so that the said projection may pass to the opposite side of the collar M⁴. When the hook is moving downward, the projection engages the rear face of the collar and forces the rod M³ against a spring N and closes said spring to another spring M'. At its lowest position the end of the projection H³ slips off of the collar M⁴ and permits the rod M³ to return to its normal position.

On the hook H is a pin H⁴, adapted to engage a cam-surface C¹⁰ on the holding-pawl C⁹. This engagement occurs on the downward movement of the hook and causes a release of the slide C⁸, so that the spring C⁶ may return it to normal position.

Reviewing the construction and operation, it will be assumed that a subscriber at the calling device illustrated wishes to call the subscriber at station No. 3,468. He removes his receiver and permits his hook H to rise in the ordinary manner. He then moves the pointer D' successively to the figures "3," "4," "6," and "8," releasing the handle each time to permit it to return to its normal position. Before turning in his signal he examines his register to see that he has made no mistake. When through talking, he hangs up his receiver, whereupon his hook descends, and the registering - dials G immediately return to their normal position. These are all of the operations of which the subscriber is directly conscious. The other operations are all automatic. Of these automatic operations the first return movement of the handle D causes the figure "3" to appear at the opening D⁴, and during the return movement the teeth of the segment B' cause F to make three electrical contacts with F², following this immediately by one contact between E and E².

The second return causes "4" to appear at D⁴, and during the return four contacts are made between F and F² and one between E and E². On the third return six contacts are made at F² and one at E², and the figure "6" appears at the opening.

On the fourth return eight contacts are

made at F² and one at E², and the figure "8" appears at the opening. Upon descent of the hook H the frictional holding of the disks G is released, so that they may return to normal position, and one contact is made between N and N'.

What I claim is—

1. In a calling device, a contact-maker, means by which it may be moved a plurality of times to make a plurality of series of electrical contacts, an indicator associated with said device, and means by which upon making such plurality of series of contacts with said contact-maker said indicator will automatically register the number of contacts made in each series.

2. In combination, a contact-maker arranged to be moved to make a series of contacts, an indicator for determining the number of contacts to be made thereby, and a register for recording the number of contacts made by said contact-maker in each series of a plurality of movements.

3. In a calling device, the combination with a contact-closing device, and means for operating it so as to make a plurality of series of electrical contacts, of a registering device associated with said contact-closing device and so arranged that it will automatically register the number of contacts in each series of contacts made by said closing device.

4. In a calling device, the combination with a contact-closing device, a hand-lever by which it may be moved, and an indicator for determining the amount of movement required for any given number of contacts, of a register associated with said contact-closing device and arranged to automatically register the number of contacts made.

5. The combination with a contact-closing device arranged to be operated successively and to make a series of contacts upon each operation, of a registering device associated with said contact-closing device and arranged to automatically register the number of contacts made upon each operation.

6. A numbered dial, a pointer adapted to be moved by hand any desired distance over said dial, a contact-maker arranged to automatically make as many electrical contacts as indicated by a movement of said pointer on said dial, and a registering device arranged to automatically register the number of contacts so made.

7. A contact-maker, means for operating it so as to make any desired number of contacts therewith, an indicator by means of which the desired number of contacts may be determined, and an automatically-operating register for registering the number of contacts made.

8. A lever adapted to be moved by hand from its normal position, an indicator by which any desired length of movement may be determined, a spring for returning said le-

- ver to its normal position, a contact-maker operated by such return movement so as to make as many contacts as indicated on said indicator by the movement of said lever, 5 and automatically-operating means for registering the number of contacts so made.
9. In combination, a contact-maker adapted to be operated a number of times in succession, an indicator for determining the 10 number of contacts made upon each operation, and a register for recording the number of contacts made by each operation of a series of successive operations.
10. In combination, a numbered indicator, 15 two contact-making devices, means by which upon operating said indicator one of said contact-making devices will make a series of contacts which series will be automatically followed by one contact made by the second 20 contact-making device, and a register for recording the number of contacts made by the first contact-making device.
11. A calling device arranged to make a series of electrical contacts, a register for recording the number of contacts so made, and a receiver-hook arranged to cause said register to return to its normal position. 25
12. A contact-maker arranged to make successive series of contacts, a series of 30 wheels or disks provided with numbers, and means by which upon each successive operation of said contact-maker a different wheel will be moved so as to register the number of contacts made by said contact-maker during 35 a corresponding operation.
13. A contact-maker arranged to be operated successive times and to make a series of contacts upon each operation, a series of wheels or disks provided with numbers and 40 means by which upon each successive operation a different wheel will be moved so as to display the number which indicates the number of contacts made by said contact-maker during a corresponding operation.
- 45 14. A contact-maker arranged to be operated successive times and to make a series of contacts upon each operation, a series of wheels each of which is adapted to display a number indicating the number of contacts 50 made by said contact-maker, and a shifting connection between said contact-maker and said wheels whereby successive operations of the contact-maker operate successive wheels.
15. A contact-maker arranged to be operated successive times and to make a series of contacts upon each operation, a series of 55 wheels provided with numbers, means by which upon each successive operation a different wheel will be moved so as to display 60 the number which indicates the number of contacts made by said contact-maker during
- a corresponding operation, and automatically-operating means for causing the moved wheels to return to their normal positions.
16. A contact-maker and means for operating it, an indicator for determining the number of contacts to be made by each operation, and a series of independently-movable wheels arranged to record the number of contacts made by successive operations. 65
17. A series of registering-wheels, a receiver-hook, means by which an elevation of said hook will cause frictional resistance to be placed upon said wheels and a depression of said hook will release such friction, means 70 by which individual wheels may be moved desired distances from their normal positions when said hook is elevated, and means by which said wheels will be automatically returned to their normal positions when said 75 hook is depressed.
18. A series of wheels, a lever movable about a pivot and provided with connections to one of said wheels, and means by which upon making a series of movements with 80 said lever said connection will be automatically shifted from wheel to wheel.
19. A contact-maker wheel and means by which it may be moved by hand any required distance from its normal position, a spring 85 for returning it to its normal position when moved, means by which the return movement will make a series of electrical contacts at one point and one extra contact at another point, and a governor for regulating the 90 speed of the return movement.
20. A contact-making wheel and means for moving it by hand any required distance, an indicator by which the required distance is determined, a spring for returning the 95 wheel to normal position when moved, means by which the return movement will make a series of electrical contacts at one point and one extra contact at another point, a governor for regulating the speed at which said 100 contacts are made, and means for recording the number of contacts made in each series of contacts.
21. The combination with a movable receiver-hook, a pivoted slide, and a contact-closing device, of means by which a rising movement of said hook will cause said slide to turn on its pivot, and means by which a descending movement of said hook will cause 105 said slide to move in its guide and operate 110 said contact-closing device.

Signed at Chicago, Illinois, this 9th day of July, 1904.
